UNITED STATES PATENT OFFICE.

ERNEST F. RENFRO, OF SCAMMON, KANSAS.

MUSIC-LEAF TURNER.

1,146,815.

Specification of Letters Patent Patented July 20, 1915.

Application filed January 2, 1912. Serial No. 669,011.

To all whom it may concern:

Be it known that I, ERNEST F. RENFRO, a citizen of the United States, residing at Scammon, in the county of Cherokee, State 5 of Kansas, have invented certain new and useful Improvements in Music-Leaf Turners; and I do hereby declare the following to be a full, clear, and exact description of the invention, such as will enable others skilled in the art to which it appertains to 10 make and use the same.

This invention relates to new and useful improvements in music leaf turners and more particularly to music leaf turners especially adapted for use in connection with sheet music, it being understood however, that the same may be used for turning loose leaf music, music book leaves etc.

In the present instance it is my purpose 20 to provide a music leaf turner having a plurality of turning members adapted to be operated to bring a selected sheet into proper position for reading by the actuation of one leaf turning member and reversing the leaf when desired by means of a second member 25 which returns the leaf without reversing the position of the first member.

Another object of this invention is the provision in a music leaf turner of a plurality of hinged leaf turning members, means for retaining them in their proper positions and means for releasing the same in their proper relation with respect to each other.

35 A further object of this invention is to improve and simplify devices of this character, rendering them comparatively simple and inexpensive to manufacture, reliable and efficient in use and readily operated.

40 With the above and other objects in view, this invention resides in the novel features of construction, formations, combinations and arrangements of parts to be hereinafter more fully described, claimed and illustrated 45 in the accompanying drawings, in which —

Figure 1 is a front elevation of my invention. Fig. 2 is a rear elevation thereof, with parts removed. Fig. 3 is a vertical transverse sectional view taken on the line 3—3 50 of Fig. 1. Fig. 4 is a horizontal sectional view taken on the line 4—4 of Fig. 1. Fig. 5 is an enlarged fragmentary sectional view taken on the line 5—5 of Fig. 1, and Fig. 6 is a detail view of one of the latches.

55 Referring to the accompanying drawings by similar characters of reference through-

out the several views, the numeral 10 designates generally my improved music leaf turner. This music leaf turner 10 comprises a base 11 which is adapted to be supported upon a music rack of any description, and being provided upon its rear side adjacent its corners with buffers 12, prevents any undesired marring or scratching of the said rack.

The base 11 is substantially rectangular in 60 formation and is provided in its front face intermediate the ends thereof and adjacent its upper and lower edges with recesses 13 and 14 in which are supported by brackets 15 and 16, pairs of spaced parallel supporting rods 17 and 18.

The rods 17 and 18 are formed at intervals throughout their lengths with spaced circumscribing grooves 20 and 21 which receive 70 the eyes 22 formed upon the inwardly extending legs 23 of U-shaped leaf turning members 24 and 25.

The brackets 15 and 16 are held against 80 any undesired displacement by their engagement with the opposite sides of the grooves 13 and 14 and by plates 26 and 27 which close the opposite ends of the said recesses and contact with the laterally extending ends of the brackets in which the rods 17 85 and 18 are journaled.

The legs 23 of the leaf turning members 24 and 25 operate in channels 28 which lead from the recesses 13 and 14, while the angular corners of the said members 24 and 90 25 are engaged by resilient stops 29 which hold them in spaced relation to the front face of the base 11 for a purpose to be later disclosed.

A music leaf rest formed of a row of pegs 95 or pins 30 extends longitudinally of the base 11 in spaced relation from the lower edge thereof and serves to support the outer sheets of a piece of music while extending vertically with respect to the base 11 and in 100 spaced parallel relation thereto is a rod 31 off-set at its lower end as at 32 to engage the upper of the plates 27 to which one end is secured, and engaged at its upper end by a spring catch 33 which holds the said rod 105 31 against any undesired displacement. A plurality of spring clips 34 are secured at intervals to the rod 31 for engagement with the inner leaf of the music.

As illustrated in the drawings the sheet 110 turning members 24 are arranged three in number and upon the left of the base 11

when the same are in an inoperative position, while the sheet turners 25 are arranged upon the right of the base 11 when in an inoperative position and are preferably two in number as illustrated, it being understood however that I am not to be limited to any special number of leaf turners but may employ as many as is desired to operate a desired number of sheets.

10 The leaf turners 24 and 25 are yieldingly held in their inoperative positions by springs 35, but it will be readily seen that they each may be moved to the reversed sides of the base 11 against the tension of the said springs in which positions they may be held against displacement by latches 36 operating through slots 37 formed in the said base 11 at convenient points thereon.

15 It is to be noted that the springs operating the members 25 are more highly tensioned than to operate the member 24. By this means when the leaf has been turned by the member 24 it can be turned back by the member 25 as this will carry the member 24 20 with it in the backward movement.

25 The latches 36 are bodily movable through the slots 37 to and from the angular corners of the members 24 and 25 and are supported by sliding rods 38 to which they are 30 pivotally secured as indicated by the numerals 39.

35 Each of the rods 38 is slidable through an ear 40 formed upon a supporting plate 41 which closes the pockets 42 in which the rods 38 are located, while supported by the said ear 40 and a similar ear 43 formed upon the opposite end of the plate 41 is a U-shaped supporting rod 44 upon which is 40 slidably located a sliding plate 45 mounted on the rod 38 and which engages one end of a spring 46 which bears upon the ear 40 serving to normally retain its latch 39 in a locking position.

45 Bell crank levers 47 are pivotally connected to the base 11 in recesses 48 formed upon the rear side thereof and are connected by operating rods 49 to the rods 38 in such manner that upon the operation of the bell crank levers the latches will be moved from 50 their engagement with the members 24 and 25 serving to release the same and permitting them to be swung by the springs 35 to the reverse sides of the base 11 for a purpose to be later disclosed.

55 Forwardly extending bracket arms 50 are extended from the opposite ends of the slot 51 and are connected at their outer terminals as shown in Figs. 1 and 5 by a rod 52 upon which are journaled operating levers 53 connected at their rear extremities to the bell crank levers 47 by operating rods 54.

60 The forward terminals of the operating levers 53 are bifurcated as at 55 to receive the forward ends of the operating arms 56, 65 which by their engagement with the beveled

shoulders 57 of the said levers 53 serve when depressed to actuate the levers 53 thus moving the rods 54 to operate the bell-crank lever and consequently release the latches 36.

70 The free ends of the arms 56 are spread apart as indicated by the numeral 58 to provide a means whereby any one of them may be pressed without interfering with the adjacent arms.

75 The device is used as follows:—The outer attached sheets of the music are inserted under the members 24 and 25 until the intermediate portion is located below the rod 31. The members 24 and 25 are next moved to the reversed sides of the base 11 in which 80 position they are retained by the latches 36 against the tension of the springs 35. The intermediate leaf of the music is next hingedly secured to the rod 31 by means of the spring clips or catches 34 and the 85 members 24 and 25 turned to the position shown in Fig. 1 of the drawings.

90 The device is now ready for operation and upon depressing the operating lever 56 located at the extreme right of the device, 95 the turning arm connected with said lever will be released by the latch thereof, and under the influence of the spring will swing to the opposite side of the base carrying with it the music sheet. By pressing the 95 next lever, the arm connected thereto which is positioned opposite to the first mentioned arm will be released, and moving to the other side of the base will carry with it the leaf, or in other words turn the same back. 100 This operation may be continued with the various sheets and the several arms of the 105 turner as will be evident. In other words it will be noted that the arms 24 and 25 move in opposite directions under the influence of their respective springs and that when the levers of such arms are depressed, the latches holding such arms are released to permit the spring to swing such arms. Furthermore, it will be seen that each turning arm is provided with an independent 110 spring, and is latched and released independently of any of the other arms.

115 From the foregoing disclosures taken in connection with the accompanying drawings it will be manifest that a music leaf turner is provided for which will fulfil all of the necessary requirements of such a device.

120 Having thus fully described this invention what I claim as new and desire to protect by Letters Patent, is:—

1. In a music leaf turner a plurality of sets of oppositely operating leaf turning members the members of one set severally constructed and arranged to turn a music leaf the members of the other set severally constructed and arranged to return the leaf to its first position without reversing the 125 position of the member of the first set and 130

means for actuating the members of each set of leaf turning members.

2. In a music leaf turner a set of reversible leaf turning members constructed and arranged severally to turn a leaf a second set of similar members constructed and arranged to return the leaf to its first position without disturbing the position of the turning member and means for actuating both sets of leaf turning members independently.

3. In a music leaf turner a reversible leaf turner constructed and arranged to turn a leaf, a second leaf turner adapted to reverse the leaf without disturbing said first leaf turner and means for actuating said leaf turners.

4. In a music turner in combination, a

frame adapted to hold a music sheet swinging arms constructed and arranged to engage said sheet springs in connection with said arms to turn the leaves individually swinging replacer arms on the side to which said first arms move in turning the sheets means for retaining said first arms means for releasing said first arms individually, means for releasing said replacer arms to return the sheet without returning said first arm.

In testimony whereof, I affix my signature, in presence of two witnesses.

ERNEST F. RENFRO.
